ATTORNEY

UNITED STATES PATENT OFFICE.

WILLIAM H. ESENWEIN, OF BELLEVUE, PENNSYLVANIA.

SWIMMING FROG.

1,393,518.

Specification of Letters Patent.

Patented Oct. 11, 1921.

Application filed June 8, 1920. Serial No. 387,440.

To all whom it may concern:

Be it known that I, WILLIAM H. ESENWEIN, a citizen of the United States, residing at Bellevue, in the county of Allegheny and State of Pennsylvania, have invented new and useful Improvements in Swimming Frogs, of which the following is a specification.

This invention relates to animated toys, 10 and more particularly to what I term a swimming frog.

One of the main objects of the invention is to provide a device of the character stated of simple construction and operation which 15 may be produced at small cost. A further object is to provide a device having simple and efficient means for propelling the same in a lifelike manner. Further objects will appear from the detailed description.

20 In the drawings:—

Figure 1 is a top plan view of a device constructed in accordance with my invention.

25 Fig. 2 is a view similar to Fig. 1 with the top section of the body or casing removed.

Fig. 3 is a central longitudinal vertical section through the device, the operating mechanism and associated parts being shown in elevation.

30 In constructing the device I provide a sheet metal body 1 which is formed of an upper section 2 and a lower section 3 secured together in any suitable or preferred manner. At the forward portion of lower 35 section 3, and adjacent each side thereof, I provide an opening through which projects a front leg member 4, these members being connected at their inner ends by a bridge piece 5. As will be understood, this piece

40 5 and the leg members 4 may be readily formed by bending from a strip of material of suitable length and width. Bridge piece 5 supports the lower end of a drive shaft 6, rotatably mounted within body 1,

45 the upper end of this drive shaft being mounted through a bracket 7 secured to section 2. A pinion 8 is secured on shaft 6 adjacent to the lower end thereof and meshes with a gear 9 secured to the lower 50 end of a drum 10 loose on winding shaft 11.

A spring 12 has one end secured to gear 9 and is wound around drum 10, the other end of this spring being secured to the ratchet-wheel 13 secured on the winding 55 shaft. The winding shaft extends through

upper section 2 of the casing and is provided with a key 14 secured thereon. As will be readily understood, by turning shaft 11 the spring is wound, ratchet 13 being held against reverse rotation by a spring 60 pawl 15 secured to one side of body 1. After the spring has been wound upon the drum 10 it will act through gear 9 and pinion 8 to rotate drive shaft 6.

Drive shaft 6 is provided adjacent to its 65 upper end with a crank 16 which is connected by a pitman 17 to a rod 18 which connects the movable elements 19 of the back legs of the frog. The elements 19 are connected by a bridge piece 20 and constitute there- 70 with a substantially inverted U-shaped member which is formed by bending from a strip of sheet metal of suitable width and length. Each of the elements 19 is pivoted at 21 to the lower arm 22 of an upper leg 75 member 23 which is secured to body 1. Member 19 is provided at its lower end with two spaced stop fingers 24 and 25 which are disposed at right angles to each other, finger 24 being in alignment with element 19. 80 A substantial triangularly shaped foot member 26 is pivoted at 27 to the lower end of element 19 between the fingers 24 and 25. Rotation of shaft 6 will serve, through the medium of crank 16 and pitman 17, to re- 85 ciprocate elements 19. During upward movement of the forward ends of elements 19 the foot members 26 will swing into substantially vertical position, downward movement of these members being limited 90 by fingers 25. During downward movement of the forward ends of elements 19, foot members 26 will be held in substantially horizontal position by fingers 24 so as to exert pressure upon the water and cause 95 forward travel of body 1, this operation representing in a general way the movement of a frog when swimming.

What I claim is:—

1. In a swimming toy, a body, a member 100 of substantially inverted U-shape pivotally connected to the body for rocking movement on a horizontal axis, the arms of said member forming legs, means for rocking said U-shaped member and foot members 105 pivoted to the free ends of the legs and having their upward movement relative to the legs limited.

2. In a toy, a body, upper leg members secured to said body, a member of substan- 110

tially inverted U-shape pivoted between said leg members for rocking movement on a horizontal axis, the arms of the U member forming lower leg members and being provided at their forward ends with forwardly projecting abutment elements, foot members pivoted to the forward ends of said lower leg members for movement on a horizontal axis and positioned below said abutment elements, and means for rocking said U-shaped member.

3. In a toy, a body, upper leg members secured to said body, a member of substantially inverted U-shape supported between the leg members for movement on a horizontal axis, the arms of said U member being directed forwardly of the body and forming lower leg members, a rod connected to the U-shaped member above the axis of movement thereof, and means for reciprocating said rod.

4. In a toy, a body, a member of substantially inverted U-shape secured to the body, the arms of said member forming fore legs for the body, hind legs movably connected to the body, a motor, a drive shaft having one end supported by the bight portion of said U-member, driving connections between said motor and the shaft, and connections between said shaft and the hind legs for imparting motion to the latter.

5. In a swimming toy, a body, a member of substantially inverted U-shape positioned in the forward portion of the body and having its arms extending through the same to form forward leg members, upper

leg members secured to the body at opposite sides of the rearward portion thereof, lower leg members pivoted to said upper members for rocking movement about an axis extending transversely of the body, foot members connected to said lower leg members, a crank shaft mounted within the body and having its lower end portion supported by the bight portion of said inverted U-shaped member, means for rotating said shaft, and connections between the crank shaft and the lower leg members for rocking the latter about their pivotal axes.

6. In a swimming toy, a body, a member of substantially inverted U-shape positioned within the forward portion of the body and having its arms extending through the same to provide forward leg members, upper leg members secured to the opposite sides of the rearward portion of said body, a member of substantially inverted U-shape pivoted between said upper leg members and having its arms projecting downwardly and forwardly therefrom to form lower rear leg members, foot members carried by said lower rear leg members, a crank shaft rotatably mounted within the body and having its lower end portion supported by the bight portion of the forward inverted U-shaped member, means for rotating said shaft, and connections between the crank shaft and the rearward inverted U-shape member for rocking the same about its pivotal axis.

In testimony whereof I affix my signature.

WILLIAM H. ESENWEIN.
